GLASS CUTTER

Lucien Lefebvre, Timmins, Ontario, Canada

Application January 8, 1945, Serial No. 571,889

6 Claims. (Cl. 49—52)

1

This invention relates to a glass cutter, and more particularly to an improved device adapted for the cutting of safety glass or the like.

A primary object of this invention is the provision of a device adapted for the cutting of glass in sheets or the like by scoring a line simultaneously and evenly on both sides.

A further object of this invention is the provision of a device particularly adapted for use in the cutting of such a glass as safety glass provided with a layer of Celluloid through the middle, wherein if the glass were scored on one side only the safety layer would preclude an even cutting or breaking of the glass.

A still further object is the provision of means in such a device whereby the glass may be evenly scored on both sides regardless of the shape of cut desired.

A still further object is the provision of means for producing an equal pressure simultaneously on cutters operable on opposite sides of the glass.

An additional object is the provision of means in such a device for varying the tension so exerted.

A still further object is the provision of an attachment for cutters whereby cuts may be made at relatively great distances from the edges of the glass.

Still further objects reside in the combinations of elements, arrangements of parts, features of construction, all as will be more fully pointed out hereinafter and disclosed in the accompanying drawings, wherein there is shown a preferred embodiment of this inventive concept.

In the drawings:

Figure 1 is a top plan view of one form of device embodying this invention, certain parts thereof being broken away.

Figure 2 is a fragmentary side elevational view of the device shown in Figure 1, enlarged.

Figure 3 is an enlarged sectional view taken substantially along the line 3—3 of Figure 1.

Figure 4 is an enlarged sectional view taken substantially along the line 4—4 of Figure 1.

Figure 5 is a sectional view taken substantially along the line 5—5 of Figure 3.

Figure 6 is an enlarged sectional view taken substantially along the line 6—6 of Figure 2.

Figure 7 is a perspective view of a constructional detail, and

Figure 8 is a sectional view of an attachment adapted to be utilized in conjunction with the device.

Like reference numerals refer to like parts throughout the several views of the drawings.

2

In the drawings, a frame generally indicated at 10 is comprised of two opposite members generally indicated at 11 and 12 including extending jaw portions 13 and 14, respectively, body portions 15 and 16, respectively, frame stops 17 and 18, respectively, designed to preclude the passage of members 13 and 14 past the point where they are in substantial horizontal alignment, for a purpose to be described hereinafter, and handle portions 19 and 20, respectively.

Members 11 and 12 are substantially identical with the exception of the fact that as shown in Figure 4, body portion 15 of member 11 is provided with a tongue 21 adapted to fit within a groove 22 formed in body portion 16 of member 12, the opposite sides of groove 22 and tongue 21 being provided with registering apertures through which is passed a pivot pin 23 headed as at 23a and 24, adapted to hold the two frame members in pivotal related assembly. Additionally, portion 13 of frame member 11 is provided with a transversely extending lug 25 having an aperture 26 therethrough, while portion 14 of frame member 12 has secured thereto, at a point opposite lug 25, a housing or guide generally indicated at 30.

Housing 30 is secured as by welding to a flange 31 secured to extending member 14, and is provided with a recess 42 therein and two longitudinally disposed slots 43 and 44 extending in parallelism substantially the entire length of housing 30 and through flange 31. Positioned within housing 30 is a nut or follower generally indicated at 45 (see Figure 7) comprised of a cylindrical portion 46 and a pair of oppositely disposed protruding lugs 47 and 48 adapted to engage within slots 43 and 44, respectively. Nut 45 is also provided with an extending portion 49 threaded as at 50, and an internal threaded bore 51.

A screw or adjusting rod 55 is adapted to engage in threaded bore 51, and is provided with a smooth extremity 52 adapted to extend outwardly through a suitable recess 53 in the end of the casing, a locking collar 54 being secured to the shank of the screw to hold the parts securely in position. A knurled knob 57 is adapted to be secured as by a set screw 58 to the extending portion of shank 52. Thus it will be seen that rotative movement of knob 57 occasions transverse movement of nut 45 within recess 42 in housing 30.

A suitable collar 60 secured as by a set screw 61 to the outer extremity of bolt 55 precludes the possibility of completely unthreading the nut 45 therefrom, unless the collar is removed.

A tension spring 62 is threadedly engaged with threaded portion 50 of extending part 49 of nut 45 and has its opposite end secured in recess 26 of lug 25 of member 13. Thus it will be seen that the spring 62 biases the members 13 and 14 toward each other, the extent of such biasing being limited by the stops 17 and 18, and the tension exerted by the spring 62 being regulated by the position of nut 45 within the housing 30.

The outer extremities of members 13 and 14 have positioned thereon identical members 65 and 66 oppositely disposed thereto. Members 65 and 66 are glass cutter holders and, as shown in Figure 6, each provided with a transverse bore 67 through which set screws 68 are adapted to extend to engage suitable recesses or depressions in the extremities of members 13 and 14 to hold the parts securely in related assembly. Members 65 and 66 are also provided with additional bores 70 preferably of rectangular cross-sectional configuration within which are adapted to be positioned conventional hand glass cutters or scoring members 71, the same being secured in position as by set screws 72 extending into the bores 70. From the foregoing it will now be seen that when it is desired to score opposite sides of a piece of glass for cutting, the handles 19 and 20 are pressed together separating the cutting edges of the cutters 71 and the device positioned over the pane of glass to be cut. When the handles are released the tension of the spring 62 causes the cutting edges to bear tightly against the opposite surfaces of the pane of glass, and the device may be guided in any desired pattern by means of the handles to produce any desired score line on opposite surfaces of the pane of glass.

Under certain conditions, as when it is desired to cut a line a relatively great distance from the edge of the plate of glass the length of members 13 and 14 may be insufficient to permit the cutters 71 to be so extended. Under such conditions an extension generally indicated at 75 (see Figure 8) is utilized. Extension 75 is comprised of a rod or shaft 76 of any suitable length and has secured to one end thereof as by welding or the like, a sleeve 77 of a diameter adapted to surround members 13 and 14, and is provided with set screws 78 engaging suitable threaded recesses therein. Depressions or detents 80 are provided adjacent the opposite end of rod 76 positioned to receive the ends of set screws 68. The manner of use of extension 75 should now be obvious, set screws 68 being released and members 65 and 66 being removed from extending portions 13 and 14. Sleeves 77 are then placed in position over the end members 13 and 14, the set screws 78 tightened, and members 65 and 66 positioned on the opposite ends of rods 76 and held in position by set screws 68. Thus it will be seen that the length of arms 13 and 14 may be effectively extended to any desired position to perform a cutting operation on any desired size and sheet of glass at any desired distance from the edge.

From the foregoing it will now be seen that there is herein provided a device accomplishing all of the objects of this invention and others including many advantages of great practical utility.

As many embodiments may be made of this inventive concept, and as many modifications may be made in the embodiment hereinbefore described and shown in the accompanying drawings, it is to be understood that all matter herein is to be interpreted merely as illustrative and not in a limiting sense.

I claim:

1. In a device of the character described, in combination, a pair of extending members, means securing said members in pivotal relation, glass cutting means carried at the extremities of said members, a housing carried by one of said members, a movable nut in said housing, a tension spring having one end secured to said nut, and the other end to the other of said members, and means for moving said nut in said housing to vary the tension exerted by said spring.

2. A glass cutting and scoring tool composed of a pair of pivoted jaws, handle means for operating said jaws and disposed on the opposite side of the pivot therefrom, glass cutting means secured to the adjacent extremities of said jaws, spring means for biasing said jaws together, a guide upon one jaw, a follower movable in said guide, said spring means being secured to said follower and to the other jaw, and means including an adjusting rod, rotatably and non-reciprocatingly mounted in said guide for moving said follower in said guide to adjustably tension said spring.

25 3. A glass cutting and scoring tool composed of a pair of pivoted jaws, handle means for operating said jaws and disposed on the opposite side of the pivot therefrom, glass cutting means secured to the adjacent extremities of said jaws, spring means for biasing said jaws together, a guide upon one jaw, a follower movable in said guide, said spring means being secured to said follower and to the other jaw, and means including an adjusting rod, rotatably and non-reciprocatingly mounted in said guide for moving said follower in said guide to adjustably tension said spring, said glass cutting means including a cutter holder carried by each jaw, a glass scoring member supported by each holder and arranged in aligned, opposite arrangement to each other for simultaneously marking opposite surfaces of a glass body interposed therebetween.

40 4. A glass cutting and scoring tool composed of a pair of pivoted jaws, handle means for operating said jaws and disposed on the opposite side of the pivot therefrom, glass cutting means secured to the adjacent extremities of said jaws, spring means for biasing said jaws together, a guide upon one jaw, a follower movable in said guide, said spring means being secured to said follower and to the other jaw, and means including an adjusting rod, rotatably and non-reciprocatingly mounted in said guide for moving said follower in said guide to adjustably tension said spring, said glass cutting means including a cutter holder carried by each jaw, a glass scoring member supported by each holder and arranged in aligned, opposite arrangement to each other for simultaneously marking opposite surfaces of a glass body interposed therebetween, each holder having a first bore for receiving said extremity and a second bore, perpendicular thereto for receiving said glass scoring member.

65 5. A glass cutting and scoring tool composed of a pair of pivoted jaws, handle means for operating said jaws and disposed on the opposite side of the pivot therefrom, glass cutting means secured to the adjacent extremities of said jaws, spring means for biasing said jaws together, a guide upon one jaw, a follower movable in said guide, said spring means being secured to said follower and to the other jaw, and means including an adjusting rod, rotatably and non-reciprocatingly mounted in said guide for mov-

ing said follower in said guide to adjustably tension said spring, said guide including a housing carried by said one jaw, spaced longitudinal slots in the wall of said housing comprising guide openings, said follower consisting of a cylindrical member having spaced lugs engageable and slideable in said guide slots, an axial threaded bore in said follower, said adjusting rod having screw threaded engagement with said bore.

6. A glass cutting and scoring tool composed of a pair of pivoted jaws, handle means for operating said jaws and disposed on the opposite side of the pivot therefrom, glass cutting means secured to the adjacent extremities of said jaws, spring means for biasing said jaws together, a guide upon one jaw, a follower movable in said guide, said spring means being secured to said follower and to the other jaw, and means including an adjusting rod, rotatably and non-reciprocatingly mounted in said guide for moving said follower in said guide to adjustably tension said spring, said glass cutting means including a cutter holder carried by each jaw, a glass scoring member supported by each holder and arranged in aligned, opposite arrangement to each other for simultaneously marking opposite sur-

10

faces of a glass body interposed therebetween, said guide including a housing carried by said one jaw, spaced longitudinal slots in the wall of said housing comprising guide openings, said follower consisting of a cylindrical member having spaced lugs engageable and slideable in said guide slots, an axial threaded bore in said follower, said adjusting rod having screw threaded engagement with said bore.
